UNDERREAMER

Weyman B. Dunlap, Jr., Corpus Christi, Tex., assignor to Delta Foundation Company, Inc., a corporation of Texas

Application April 16, 1938, Serial No. 202,443

9 Claims. (Cl. 255—74)

The invention relates to under-reamers of the type which is employed in under-reaming shallow holes for piling, foundation supports, and the like.

5 One use to which the invention may be put is the under-reaming of holes drilled to receive the piles or foundation supports of building structures. It has become more or less customary in 10 to under-ream the lower end of the hole after it has been dug so as to increase the width of the base upon which the weight is supported.

15 It is an object of this invention to provide an under-reamer for enlarging the lower ends of holes of this character which will operate positively and accurately to enlarge the opening to the desired extent.

20 I desire to provide an under-reamer having laterally expanding blades and to provide mechanism whereby the blades may be uniformly expanded in a lateral direction so as to cut a flat bottom hole.

25 It is a further object of the invention to provide a cutting blade upon an under-reamer for this purpose which will move the cuttings from the blades toward the interior where they may be received within the bucket.

30 It is a further object of the invention to so form the bucket in connection with the expanding blades that when the tool is removed from the hole the earth cuttings in the bucket may be readily dumped so that the tool may be ready for use.

35 The invention resides largely in the particular construction and arrangement of the parts which make up my improved under-reamer and for a better understanding thereof reference is made to the accompanying drawings.

40 In Fig. 1 is a central longitudinal section through my improved device, certain parts being shown in elevation.

45 Fig. 2 is a similar side view taken at right angles to the view shown in Fig. 1 and with parts broken away along the central longitudinal section.

Fig. 3 is a side view similar to the Fig. 1 view but with the blades shown in expanded position.

Fig. 4 is a top plan view of the device.

50 Fig. 5 is a transverse section on the plane 5—5 of Fig. 1.

Fig. 6 is a bottom plan view of the device.

Fig. 7 is an assembly view showing the device as employed in under-reaming.

55 The body of the housing for my device is formed as a cylindrical bucket 1 of heavy sheet

metal. The lower end of this bucket is formed with an approximately disc-shaped closure plate 2, which is hinged at 3 to a stationary portion of the bottom. This structure will be understood best from Fig. 6. On the inner side of the closure plate 2 and opposite the hinge 3 is an upwardly extending staple 4 to engage with a latch rod 5.

The latch rod 5 is pivoted toward the upper end of the bucket at 6. This pivot pin is mounted 10 upon a block 7 secured to the side wall of the bucket. The latch rod 5 extends above the pivot and has an upper handle 8 whereby the rod may be moved laterally so as to engage or disengage the hook 8' with the staple 4. This will be understood from Fig. 1.

Centrally of the bottom closure plate is a supporting lug or boss 9, which projects a short distance below the plate and acts as a support on which the bucket may be rotated. On each side of 20 the supporting post are openings 10, at the rearward sides of which are mounted cutting blades 11. These blades extend but a short distance below the plate and act merely to scrape up and scoop into the lower end of the bucket such cuttings as may be found upon the bottom of the hole.

25 The cutters comprise two cutting blades 12. These blades, as shown particularly in Fig. 2, are spaced apart relative to the axis of the bucket and one blade is adapted to move laterally through a slotted opening 13 in the side of the bucket while the other blade extends laterally from the opposite side through a similar slot 13 in the bucket.

With reference particularly to Fig. 2, it will 35 be seen that there are two spaced plates for each of the blades. There is an outer plate 14 and an inner plate 15 between which each blade 12 is movably mounted. Toward the center portion of each of the plates 14 and 15 there is an upwardly extending notch 16 in the lower side, as shown best in Fig. 1. This notch allows a limited upward movement therein of the heads 17 of the cross shaft 18. Said shaft extends radially outward from the drive stem or kelly 19 through openings in the blades 12 and thus form driving members through which a downward thrust on the blades may be accomplished.

45 The drive stem or kelly 19 is preferably polygonal in cross section so that it may be engaged for rotation by any appropriate device at the surface. The shaft 18 upon which the blades 12 are supported extends centrally through the lower end of the kelly and it will be seen that a down- 50

ward thrust upon the drive stem 19 will move the blades 12 downwardly.

In their downward movement the blades are guided by means of pins working in cam slots in the blade. There is an upper cam slot 20 in each blade through which a pin 21 extends. Said pin 21 is extended through the lower ends of the spaced plates 14 and 15 and is held in a stationary position while the blades are being moved. The slots 20 are curved in a proper direction so as to force the blade in its downward movement in a lateral direction at the lower end.

There is a second pin 22 on the opposite side of the blade and at a point spaced upwardly from the lower end of the blade. This pin is supported in a cross plate 23 in the housing. As will be seen from Fig. 5, the cross plate 23 is spaced at one side of the center of the bucket and in proper position adjacent the outer face of the cutting blade 12. Said pin 22 is formed on the inner end of a stud 32 which is screwed through the supporting plate 23 and fits within a cam slot 24 in the blade. As will be noted this cam slot is formed approximately on the arc of a circle and extends in the opposite direction from the slot 20 at the upper end of the blade.

The lower ends of each of the blades are inclined upwardly and rearwardly from the forward cutting edge 25. This sloping lower edge 26 of the blade is formed at such an angle that when the blades are properly expanded the sloping edge will be lying in position engaging with the bottom of the hole. On the forward side of each of the cutting blades is formed a cutting or scraping member 27. This cutting member extends in the direction of rotation of the tool and serves to engage the side of the hole with a scraping and cutting action which moves the material toward the interior of the bucket. There is a lower blade indicated in dotted lines in Fig. 2 at 28, which cuts along the bottom of the hole and also serves to retain the material so that it may be moved toward the interior of the bucket.

In the operation of my device the blades will be in contrasted position fitting within the bucket, as shown in Fig. 1. When a hole has been drilled, as shown in Fig. 7, at 29, my device may be lowered to the bottom of the hole so that the supporting post 8 will rest upon the bottom and serve as a center about which the bucket may be rotated. The drive stem 19 may be engaged by any appropriate mechanism at the surface and rotated with the usual righthand rotation, as viewed from the upper end. As the bucket is rotated a downward thrust will be exerted upon the drive stem 19 tending to push the blades directly downward. In this downward movement of the blades an expanding force will be exerted due to the pins 21 and 22 engaging within the cam slots 20 and 24, respectively, in the blades to force the lower end of the blade radially outward. The rotation of the tool will bring these blades into cutting contact with the side of the hole and the material will be gradually reamed away from the bottom as the blades are progressively advanced outwardly. When the blades have been advanced to such an extent that the pins 21 and 22 engage in the upper ends of the cam slots in which they are moving, the hole will be fully enlarged. The extent to which the blades can be moved, will, of course, be regulated by the size of the blades and the length of the cam slots. In removing the tool an upward pull on the kelly will withdraw the blades to the Fig. 1 position

through the engagement of the pins in the cam slots.

It will be noted in the movement of the blades that the lower cutting end 25 will be moved outwardly so as to cut a flat bottom hole. This lower cutting end does not move in the arc of a circle but is thrust straight out so that when the underreaming has been finished they will lie as shown in Fig. 7 with the lower edge 26 in a horizontal direction so that the bottom of the hole will be also horizontal. It will be seen that the material scraped away from the side wall of the hole in enlarging the opening will be moved inwardly into the bucket so that the bucket may be pulled upwardly out of the hole to remove cuttings at any time, and it may be of advantage at some time during the under-reaming operation to empty the contents of the bucket so that the enlarging of the hole may be more easily accomplished. It is not intended that the blades 11 on the closure plate at the bottom of the bucket will assist in the under-reaming. They simply tend to move cuttings which may gather around the bottom into the interior of the bucket and thus leave a clean bottom to the hole.

When the bucket is removed from the hole the contents thereof may be discharged by the use of the latch rod 5. There may be a spring, as shown at 30 in Fig. 4, to hold the latch rod in latched position but the movement of the upper end of the rod or lever will unlatch the lower closure in such form as to allow the contents to be readily removed at any time.

What is claimed as new is:

1. A device for under-reaming holes, comprising a cylindrical bucket, a pair of offset outwardly extensible cutting blades therein, slotted openings in said bucket to allow movement therethrough of said blades, a drive shaft pivotally connected with the upper ends of said blades, transverse pins mounted on said bucket and engaging through cam slots in each of said blades, said slots being curved whereby the downward movement of said blades relative to said pins by said drive shaft will cause the lower ends of said blades to be moved outwardly against the wall of the hole.

2. A device for under-reaming holes, comprising a cylindrical bucket, a pair of offset outwardly extensible cutting blades therein, slotted openings in said bucket to allow movement therethrough of said blades, a drive shaft pivotally connected with the upper ends of said blades, upper and lower cam slots in said blades, pins fixed in said bucket extending through each of said slots, said slots being so curved that when said blades are moved downwardly by said drive shaft, the lower ends of said blades will be moved outwardly in a horizontal direction.

3. In a device of the character described, a cylindrical bucket, a pair of reaming blades normally housed therein, but adapted to be projected through slots in said bucket, lateral plates slidably supporting the upper ends of each of said blades, pins in said plates extending through cam slots in said blades, cam slots in said blades adjacent the lower ends thereof, pins supported in said bucket and extending through said last mentioned slots, and means to move said blades downwardly and simultaneously rotate said bucket.

4. In a device of the character described, a cylindrical bucket, a pair of reaming blades normally housed therein but adapted to be projected through slots in said bucket, lateral plates slid-

ably supporting the upper ends of each of said blades, pins in said plates extending through cam slots in said blades, means to move the lower ends of said blades laterally as they are moved downwardly, and a drive shaft pivotally connected with the upper ends of said blades to move said blades downwardly and simultaneously rotate said bucket.

5. In a device of the character described, a bucket, a closure plate for the lower end thereof, a downwardly presented boss on said plate to support said bucket as it is rotated, means to latch said closure plate, a pair of laterally movable reaming blades in said bucket, a drive shaft secured to said blades to communicate a downward thrust thereto, and stationary means in said bucket engaging each of said blades to deflect the lower end of each blade outwardly in an approximately radial direction as the bucket is rotated.

10. 6. In a device of the character described, a bucket, a closure plate for the lower end thereof, a downwardly presented boss on said plate to support said bucket as it is rotated, means to latch said closure plate, a pair of laterally movable reaming blades in said bucket, a drive shaft secured to said blades to communicate a downward thrust thereto, and means associated with said bucket and engaging with cam surfaces adjacent both ends of said blades to cause the lower end of each blade to be moved horizontally outwardly as said shaft is moved downwardly and rotated.

15. 7. In a device of the character described, a bucket, a closure plate for the lower end thereof, a downwardly presented boss on said plate to support said bucket as it is rotated, means to latch said closure plate, a pair of laterally

movable reaming blades in said bucket, a drive shaft secured to said blades to communicate a downward thrust thereto, stationary means in said bucket engaging each of said blades to deflect the lower end of each blade outwardly in an approximately radial direction as the bucket is rotated, and forwardly extending scraping means on the outer and lower edges of said blades to scrape the bottom and side walls of a bore hole.

10. 8. In an under-reamer, a bucket having cutter receiving slots therein, a closure plate for the lower end of said bucket, a manually operable latch to retain said plate in closed position, means on said plate to rotatably support said bucket, a drive shaft, blades pivoted thereto at their upper ends, and stationary means on said bucket to engage said blades and move the lower ends radially outward as said blades are forced downwardly by said shaft.

15. 9. In a device of the character described, a cylindrical bucket, a pair of reaming blades normally housed therein but adapted to be projected through slots in opposite sides of said bucket, lateral plates slidably supporting the upper ends of each of said blades, means associated with said bucket and engaging said blades, responsive to the downward movement of said blades to direct the movement of the upper ends of said blades laterally relative to the axis of said bucket, separate means to move the lower ends of said blades laterally as they are moved downwardly, and a drive shaft pivotally connected with the upper ends of said blades to move said blades downwardly and simultaneously rotate said bucket.

20. 25. 30. 35. WEYMAN B. DUNLAP, JR.
